DESIGN FOR A PISTON

John Flammang, University City, Percy L. Bowser,
St. Louis, William M. Venner, Richmond
Heights, and Percy L. Bowser, Jr., University
City, Mo., assignors to The Sterling Corpora-
tion, St. Louis, Mo., a corporation of Delaware

Application August 3, 1938, Serial No. 79,064

Term of patent 14 years

To all whom it may concern:

Be it known that we, John Flammang, Percy L. Bowser, William M. Venner, and Percy L. Bowser, Jr., citizens of the United States, residing respectively at the city of University city, county of St. Louis, in the State of Missouri; at the city of St. Louis, State of Missouri; at the city of Richmond Heights, county of St. Louis, State of Missouri; and at the city of University city, county of St. Louis, State of Missouri, have invented a new, original, and ornamental Design for Pistons, of which the following is a specification, reference being had to the accompanying drawing, forming part thereof.

Figure 1 is a perspective view of a piston showing our new design. The opposite side of the piston is substantially like the side shown.

Figure 2 is a horizontal section taken through the wrist pin axis looking downwardly toward the open end of the piston.

We claim:

The ornamental design for a piston, substantially as shown and described.

JOHN FLAMMANG.
PERCY L. BOWSER.
WILLIAM M. VENNER.
PERCY L. BOWSER, JR.
